UNITED STATES PATENT OFFICE.

EVARISTE BERTHIAUME AND ALVAREZ BERTHIAUME, OF ST. HYACINTHE, QUEBEC,
CANADA, ASSIGNORS TO OVIDE BROUILLARD, OF MONTREAL, QUEBEC, CANADA.

ROSSING MACHINE.

Application filed August 1, 1922. Serial No. 578,888.

To all whom it may concern:

Be it known that we, EVARISTE BERTHIAUME and ALVAREZ BERTHIAUME, both subjects of the King of Great Britain, and residents of 5 St. Hyacinthe, Province of Quebec, Dominion of Canada, have invented certain new and useful Improvements in Rossing Machines, of which the following is a specification.

10 Our invention relates to that class of rossing or barking machines wherein two sets of wheel-like elements are employed to roll a log over and over, and at the same time to feed it past one or more cutters which 15 act to remove the bark from it, our improvements being particularly directed to means for making proper allowances for the reduction in size of the log as it progresses through the machine, so that it will maintain 20 a uniform and steady rate of progression, a proper relation to the barking knives, and will be duly discharged from the machine, at the completion of the barking operation, without variations or complications.

25 The particular type of machine to which our improvements relate is illustrated in United States Patent No. 924,918, of June 15, 1909, to Joseph Moreau; and to that 30 patent reference may be made for particulars of construction other than those which we will now explain and point out.

In the drawings, Fig. 1 is a plan view, partly in section, of a machine embodying 35 our improvements; Fig. 2 is a cross sectional view, taken as on the line 2-2 of Fig. 1, looking to the left; and Fig. 3 is a diagrammatic plan of the more important log rolling and feeding elements of the machine, taken 40 as though looking in the direction of the arrow in Fig. 1, and showing a log in two positions during its progress through the machine. The relative difference in the sizes of the rolling and feeding wheels is exaggerated in the drawings, as is also the reduction in size of the log, in order to make more plain the principle involved in our improvements.

In all of the figures similar parts are 50 designated by similar reference numerals.

In the frame 1 of the machine is mounted

the driving shaft 2, which carries the knife heads 3 and 4, which normally revolve inward, toward the center of the machine, so that their knives strike downward against 55 the log to be barked. While, on bearings loosely surrounding the shaft 2, are mounted a series of log rolling wheels 5, 6, 7, 8, 9 and 10, which are revolved in a direction opposite to that of the cutter heads, so as to roll 60 the log upward to meet the downward strokes of the barking knives. This reverse movement of the rolling wheels is obtained by transferring the drive from the main shaft 2 through a pulley 17, belt 18, and 65 pulley 19 to a shaft 20, from which it is carried by a sprocket wheel 21, sprocket chain 22, and sprocket wheel 23 to a counter-shaft 24 on which are mounted pinion gears 25, 25, meshing with gear wheels 26, 26, each 70 of which is secured to one of the rolling wheels 5 to 10 inclusive.

The shaft 20 carries a series of bevelled pinions 27, 27, severally meshing with bevelled pinions 28, 28, on sleeves 29, 29, 75 carrying pinions 30, 30, meshing with gear teeth 31, on rolling and feeding disks 12 to 15, inclusive, each mounted on a pintle 32, carried in the head of a post 33, which is revolvably mounted in a vertical sleeve 34 80 carried by the frame of the machine. Also, connected to each post 33, is an arm 35, on which one of the sleeves 29 is journaled, the free end of the arm having a ball and socket connection with a sleeve 36 on the shaft 20. 85 Hence, longitudinal movement of the shaft 20 will change the angle of inclination of the disks 12, 13, 14 and 15, relative to the line of movement of the log 37.

Idler disks 11 and 16 are rotatably mounted on the frame of the machine; but they are not necessarily adjustable to varied angles of inclination to the log, it being usually sufficient to set them at an approximately normal angle.

It will be seen from the foregoing that the rolling and feeding disks 12, 13, 14 and 15 turn in the same direction as the wheels 5 to 10 inclusive, so that a log lying in the angle between the disks and wheels will be 100 rolled over and over by them, this operation being assisted by teeth or serrations 38 on

the peripheries of the disks, and by toothed sections 39 upon the faces of the wheels 5 to 10, inclusive, such sections being preferably disposed at an angle corresponding to 5 the normal angle of inclination of the disks 11 to 16 inclusive.

When, in practice, a log is entered into the machine by being laid in the angles between wheel 5 and disk 11, and wheel 6 and 10 disk 12, the rotation of the wheels and disks will roll it around on its longitudinal axis and will feed it toward the opposite end of the machine and past the cutter head 3 which will remove the greater part of the 15 bark, knots and the like from the log, thus diminishing the diameter of the log. Consequently, if the wheels are all of the same diameter and are set on a common axis, and the disks are all of the same diameter and 20 are pivoted at the same distance from the wheels, the reduced end of the log, as it advances, will not find the same support or grip from wheel 7 and disk 13 as it received from the preceding wheels and disks, be- 25 cause its butt is still held by the two preceding pairs of wheels and disks, and it cannot drop down into proper relation with the third pair so long as the first pair still grips it. This situation will recur when the log passes 30 the second cutter head and is, progressively, still further reduced in diameter. Hence, the log will tend to rock and tremble in the machine and to be unevenly acted upon by the cutters.

35 To remedy this, we vary the size of the wheels and disks, so as to compensate for the reduction of the diameter of the log in the rossing process.

Wheels 5 and 6 and disks 11 and 12 receive 40 the log in its initial condition, and hence, preferably, are all made of the same diameter. The cutter of head 3 will reduce the diameter of the log a substantial amount, for instance, one inch; and to compensate 45 for this we increase the diameter of wheels 7 and 8 and disks 13 and 14 one half inch each. The diameter of the log is still further reduced by the action of cutter head 4, for instance, another inch; and to compensate 50 for this we increase the diameter of wheels 9 and 10 and disks 15 and 16 another one half inch each.

The result is that when the reduced end of 55 a log approaches the next wheel and disk pair, it finds their peripheries close enough together to grip and support it in its normal line of advance, and it will be carried forward smoothly and accurately from one to another of the wheel and disk pairs, until 60 it is ejected from the machine.

However, we find in practice that the logs are driven more strongly against the wheels than against the disks, so that the teeth of the wheels sink into the logs deeper than 65 the teeth of the disks. This introduces a

certain element of lateral variation into the longitudinal movement of the logs, which it is desirable to overcome. For instance, when the forward end of the log approaches wheel 10 and disk 16 it has a tendency to be deflected towards the wheel, and to strike 70 the side of the wheel instead of riding over its edge. This may be overcome by setting disk 14 in somewhat toward the center of the machine so as to press more firmly against 75 the butt of the log, and to rock its forward end back toward disk 16, and to keep the log to a true course between wheel 10 and disk 16.

Similar variations in the positions of 80 other disks may be made if that is found to be desirable in practice. And we wish it to be understood that what we have shown and explained relative to the principles of our improvements is to be taken as typically 85 illustrative of our invention, and not as an exclusive embodiment thereof. For it is plain that variations might be made, by the use of equivalents and the like, without departing from the spirit of our invention as claimed.

Having thus described our invention, what we claim and desire to secure by Letters Patent of the United States is:—

1. In a rossing machine, the combination, 95 with a rotary cutter, of a series of log rolling wheels increasing in diameter, from the intake to the ejection end of the machine, and a cooperating and similar series of log feeding disks.

2. In a rossing machine, the combination, 100 with a rotary cutter, of a series of pairs of log rolling wheels, each pair increasing in diameter, from the intake to the ejection end of the machine, and a cooperating and similar series of log feeding disks.

3. In a rossing machine, the combination, 105 with a rotary cutter, of a series of pairs of log rolling wheels, each pair uniformly increasing in diameter, from the intake to the ejection end of the machine, and a cooperating and similar series of log feeding disks.

4. In a rossing machine, the combination, 110 with a plurality of rotary cutters, of a series of log rolling wheels increasing in diameter, from the intake to the ejection end of the machine, and a cooperating and similar series of log feeding disks.

5. In a rossing machine, the combination, 115 with a rotary cutter, of a series of log rolling wheels increasing in diameter from the intake to the ejection end of the machine, the axes of such wheels being disposed along a straight line, and a cooperating and similar series of log feeding disks a plurality of which are journalled along a line parallel to the axial line of the log rolling wheels, while 120 one of such log feeding disks is journalled nearer than the others to the said axial line.

6. In a rossing machine, the combination, with a rotary cutter, of a series of log rolling wheels increasing in diameter from the intake to the ejection end of the machine, the axes of such wheels being disposed along a straight line, and a cooperating and similar series of log feeding disks a plurality of

which are journaled along a line parallel to the axial line of the log rolling wheels, while one of such log feeding disks intermediate of the series is journaled nearer than the others to the said axial line. 10

EVARISTE BERTHIAUME.
